COMBINED CHAIR AND HAIR DRYER

De Witt Y. Gorman, Houston, Tex., assignor to
D. Y. Gorman, Houston, Tex.

Filed Jan. 8, 1962, Ser. No. 68,214

Term of patent 14 years

(Cl. D15—3)

FIG. 1 is a front perspective view of a combined chair and hair dryer showing my new design;

FIG. 2 is a side elevational view;

FIG. 3 is a front elevational view; and

FIG. 4 is a rear elevational view thereof.

I claim:

The ornamental design for a combined chair and hair dryer, as shown.
